UNITED STATES PATENT OFFICE.

ERNEST W. GOURD, OF WEST QUINCY, MASSACHUSETTS.

ART OF KNITTING STOCKINGS.

SPECIFICATION forming part of Letters Patent No. 372,309, dated November 1, 1887.

Application filed March 21, 1887. Serial No. 231,655. (No specimens.)

To all whom it may concern:

Be it known that I, ERNEST W. GOURD, of West Quincy, in the county of Norfolk and State of Massachusetts, have invented certain 5 new and useful Improvements in the Art of Knitting Stockings, of which the following is a specification.

My invention relates to the art of knitting stockings, and has for its object the production of a method whereby a full-fashioned stocking may be produced upon a circular-knitting machine.

Heretofore, so far as I am aware, it has not been considered feasible to produce a full-fashioned seamed stocking on a circular-knitting machine, the straight frame being regarded as the only machine that could be practically employed for that purpose. I have found, however, after long and careful experiment, that this work may be performed with as great or even greater facility upon circular as upon straight or flat frames.

My invention consists in the art or method and sub-methods hereinafter described and 25 claimed.

Reference is to be had to the accompanying drawings, and to the letters of reference marked thereon, forming a part of this specification, in which drawings similar letters indicate similar parts wherever they occur.

Of the drawings, Figure 1 represents a complete stocking-web, without any widenings or narrowings, as it leaves the machine, knit in accordance with my art or method. Fig. 2 represents a side view of a stocking made up from the web shown in Fig. 1. Fig. 3 represents a complete stocking-web, with narrowings at certain points, knit in accordance with my improved art or method. Fig. 4 is 40 a side view of a stocking made up from the web represented in Fig. 3. Fig. 5 is an outline rear view of the web shown in Fig. 3. Fig. 6 is an outline view of the several parts of the web comprising the stocking portrayed in Fig. 4 before they are seamed together. Fig. 7 is a side view of the foot and ankle portions of a stocking-web having widenings and narrowings at certain points, knit in accordance with my improved art or method. Fig. 8 45 is a rear view of the web pictured in Fig. 7. Fig. 9 is a side view of the foot and ankle of a stocking made up from the web shown in Figs.

7 and 8. Figs. 10, 11, and 12 are diagrams, referred to hereinafter in explanation of my improved art or method.

In the practice of my art or method I may use a circular-knitting machine of any kind in which the cam-cylinder or needle-cylinder, as the case may be, is capable of being reciprocated to produce knitting, and in which the 6c needles are capable of being thrown out of and returned to action, and to hold the stitches thereon when out of operation—such, for example, as is shown and described in the patent to James L. Branson, No. 149,192, March 31, 1874.

It is quite common in knitting stockings on machines of the kind mentioned to take a ribbed top, knit on machines adapted to the purpose, and pick such top on the needles and 70 knit the remainder of the leg and foot portions of the stocking thereon; and in the mode hereinafter explained it may be supposed that a stocking is begun and the knitting proceeded with in this way.

Having reference to Fig. 1, let A represent the ribbed top, which is picked upon the needles (represented by the circle in Fig. 10) at the line *a a*. The knitting of the remainder of the leg portion of the stocking is proceeded 80 with by rotating the cam-cylinder until the point *b b* is reached, when the needles at the left in Fig. 10, from the point 1 to the point 2, are thrown out of action, still retaining their stitches, and knitting is performed on the needles still in action by reciprocating the cam-cylinder, as indicated by the double-headed arrows on the right in said Fig. 10, until the point *c c* is reached, producing the fabric represented by B, when the web on those needles 85 is cast off, said needles thrown out of action, and the needles before thrown out of work, and represented on the left in Fig. 10, are brought into operation, and by reciprocating the cam-cylinder, as before, the fabric C is 90 produced, the web being cast off the needles at *d d*. The web thus knit is then made up into a complete stocking, as represented in Fig. 2, by severing the part B between the lines *e e* and *f f*, trimming or raveling back 100 to said lines, then trimming along the line *g g* and in a suitable manner at the lower ends of the parts B and C, as indicated by the lines *7' 7'*, to form the toe, and, placing the parts in

position somewhat like that portrayed in Fig. 6, seaming them together along the lines $h' i' i$, completing the stocking. This manner of practicing my improved mode is intended for 5 cheap work only, the fashioning being produced wholly by trimming off portions of the web, similar to the manner of doing "cut work."

In Fig. 3 I have shown a web which is produced in a manner similar to that described with reference to Fig. 1 down to the point $b b$, when the needles on the half of the cylinder, as represented at the left in Fig. 11, are thrown out of action, still retaining their 10 loops, and knitting is proceeded with upon the needles in the other half of the cylinder by reciprocating the cam-cylinder until the point in the web indicated at $j' j$ is reached, which may be supposed to complete the heel 15 of the stocking. At said last-mentioned point at each reciprocation of the cam-cylinder a needle at each end is dropped until the point $k k$ is reached, when only the needles between the points $3 3$, Fig. 11, may be supposed to be in operation, and said needles are 20 retained in operation and the cam-cylinder is reciprocated until a web from the point $k k$ to the point $l l$ is knitted, when, one after another, the needles at each end of those in operation 25 are dropped until the point $m m$ is reached, when only the needles between the points $4 4$, Fig. 11, will be left holding loops, and these are cast off and their needles thrown out of operation. The needles indicated at the left 30 in Fig. 11 are now brought into operation, and by reciprocating the cam-cylinder a web, as pictured between the lines $b b$ and $n n$, is knitted, when it is narrowed by throwing needles out of work at each reciprocation of the 35 cam-cylinder, as before explained, until the point $o o$ is reached, which will leave only such needles as fall between the points $5 5$, Fig. 11, in operation, and from these the loops are cast off. The web is now severed along the line $j' j$ and trimmed along the line $j' j'$, if not 40 narrowed at this point, as hereinafter described with reference to Fig. 5, and the parts placed in position as portrayed in Fig. 6, when they are seamed along the lines $k' l' l' l'$ and looped 45 together along the lines $k' l$ and $l' l'$.

If desired, a web longer than is necessary to form the heel for the stocking shown in Fig. 4 may be knitted, as between the lines $j' j' j$, Fig. 5, and the fabric severed between these 50 lines and raveled or trimmed back, as described with reference to Fig. 1; and for the purpose of shaping the heel at the rear, one after another of the needles between the points $4' 4 4$ may be thrown out of action, still retaining the stitches thereon, until the point $j' j'$ is reached, which will leave the heel portion, when folded, as united between the points $k k$, with floating yarns on the inner or wrong side, which floating yarns can be trimmed off. This 55 manner of practicing my improved process will form a full-fashioned stocking with a gore,

D, knitted on the rear of the sole portion E of the foot, as shown in Fig. 4.

In Fig. 7 I have shown a web for the foot portion of a stocking, (the leg being supposed 70 to be produced as hereinbefore explained,) fashioned by transferring the stitches from certain needles to certain other needles, and bringing back into operation certain needles which have once been thrown out of action. 75

To produce a web in accordance with my method like that pictured in the last-mentioned figure, I proceed to knit from the point $b b$ to the point $o o$ by reciprocating the cam-cylinder with half the needles in operation— say those at the right of the circle between the points $1 2$ in Fig. 12. At the point $o o$ in the web I commence transferring the stitches on the needles between the points $1 6$ and $2 7$ inward, one stitch or needle at each reciprocation of the cam-cylinder throwing the end needles out of action until the point $p p$ is reached. This operation will have made the narrowings to have taken place on the needles knitting the wales $9' 9'$ at the points $6 7$ —that 80 is, certain wales $8' 8'$ will have the appearance of converging with or running into the wales $9' 9'$ knit by the needles at said points $6 7$.

At the point $p p$, I bring all of the needles in one-half of the cylinder into operation, being 85 those in operation when knitting was being performed between the lines $b' o o$, which will begin the knitting of a web, as indicated at the line $q q$, Fig. 8, when I narrow quite rapidly by transferring, say, the stitches on the last 90 three needles at each end of those in operation at each reciprocation of the cam-cylinder inward until the point $r r$ is reached, when I proceed, without narrowing, down to the point $s s$, when I narrow as between the points $q r$ 105 until the point $t t$ is reached, at which point the loops are cast from the needles in operation, (being those between the points $6 7$, Fig. 12,) and said needles are thrown out of action. Knitting is now resumed on the needles in the 110 other half of the cylinder, being those represented by the portion of the circle at the left in Fig. 12, and knitting is done by reciprocating the cam-cylinder until the point $u u$ is reached, when narrowing is performed, as between the points $s s$ and $t t$, until the point $v v$ is reached, when the web is cast off, severed 115 along the line $q q$, the parts placed in position, as represented in Fig. 6, sewed and looped together, as described with reference to Fig. 4, 120 producing a full-fashioned stocking-foot like that pictured in Fig. 9, which is of the same character precisely as full-fashioned seamed stockings knitted on what is commonly known as the "Cotton" flat frame. 125

I am by the art or method explained enabled to form a web for a complete-fashioned seamed stocking on a circular frame by a method which, so far as my knowledge extends, has never heretofore been practiced. 130

Having thus described my invention, what I claim is—

1. The improvement in the art of producing a web for a complete stocking on a circular-knitting machine, which consists in knitting the web for the leg portion as a tubular fabric, then throwing substantially one-half of the needles out of action, allowing them to retain the loops thereon, and reciprocating the cylinder to knit the heel and sole portions of the stocking-foot, then throwing the needles thus employed out of action and bringing into operation the needles previously thrown out and reciprocating the cylinder to knit the upper portion of the foot, as set forth.

2. The improvement in the art of producing a web for a complete stocking on a circular-knitting machine, which consists in knitting the web for the leg portion as a tubular fabric, then throwing substantially one-half of the needles out of action, allowing them to retain the loops thereon, and reciprocating the cylinder to knit the heel portion, gradually narrowing the fabric at the end for this purpose, and retiring the needles employed in narrowing, then bringing into operation again the needles thus retired and beginning the knitting for the sole portion by reciprocating the cylinder, narrowing and retiring needles to form the gusset D, then knitting a web of substantially uniform width and of desired length, then narrowing and retiring needles to form the sole portion of the toe, then throwing the needles thus employed out of action and bringing into operation the needles previously thrown out and reciprocating the cylinder to knit the upper portion of the foot, gradually narrowing at the end for the toe portion, as before described, substantially as set forth.

3. The improvement in the art of producing a web for a complete stocking on a circular-knitting machine, which consists in knitting the web for the leg portion as a tubular fabric, then throwing substantially one-half of the needles out of action, allowing them to retain the loops thereon, and reciprocating the cylinder to knit the heel portion, gradually narrowing the fabric at the end by transferring the loops at the ends of the series of needles in operation inward and retiring needles, then bringing into operation again the needles thus retired and beginning the knitting for the sole portion by reciprocating the cylinder, narrowing by transferring the loops, as before, and retiring needles to form the gusset D, then knitting a web of substantially uniform width and of desired length, then narrowing by transferring loops, as before, and retiring needles to form the sole portion of the toe, then throwing the needles thus employed out of action and bringing into operation the needles previously thrown out and reciprocating the cylinder to knit the upper portion of the foot and gradually narrowing at the end for the toe portion by transferring stitches and retiring needles, as before, substantially as set forth.

In testimony whereof I have signed my name to this specification, in the presence of two subscribing witnesses, this 12th day of March, A. D. 1887.

ERNEST W. GOURD.
